(57) **CLAIM**

The ornamental design for a support for a pneumatic compression controller, as shown and described.

DESCRIPTION

FIG. 1 is a front perspective of a support for a pneumatic compression controller, the pneumatic compression controller being shown in phantom;

FIG. 2 is a rear perspective of the support;

FIG. 3 is a top view thereof;

FIG. 4 is a bottom view thereof;

FIG. 5 is a front elevation thereof;

FIG. 6 is a rear elevation thereof; and,

FIG. 7 is a right elevation thereof, the left elevation thereof being a mirror image thereof.

The phantom lines in the drawings indicate environmental structure which forms no part of the claimed design.
